(57) **CLAIM**

The ornamental design for a hydraulic pump, substantially as shown.

DESCRIPTION

FIG. 1 is a front, top and right-hand side perspective view of a hydraulic pump comprising a new, original and ornamental design;

FIG. 2 is a front view thereof;

FIG. 3 is a back view thereof;

FIG. 4 is a right-hand side view thereof;

FIG. 5 is a left-hand side view thereof;

FIG. 6 is a top view thereof; and,

FIG. 7 is a bottom view thereof.

The broken line portion of the figure drawings is included to show portions of the article that form(s) no part of the claimed design.
